BRASSIÈRE DISPLAY FORM

Jacob J. Hellman, Atlanta, Ga.

Application August 19, 1952, Serial No. 305,173

2 Claims. (Cl. 223—66)

1

The present invention relates to certain new and useful improvements in respect to which ways and means are provided for displaying a brassière on a form, and the object of the invention is to provide a novel and practical means on the form, so that it is possible to dispense with the use of pins, whereby to obviate the damage to the brassière and so that if the latter is wanted by a particular customer, it can be removed from the form, completely unmarked and ready for sale.

It is a matter of common knowledge that forms which are commonly in use in store windows and elsewhere, make it necessary to use pins of one type or another, with the result that in order to make the brassière fit the form with requisite nicety and in a manner of proper display, the positions of the pins have to be changed and the overlapped ends of the brassière are punched full of holes and the brassière becomes unsalable. For this reason, there has long existed the need for a form with means thereon to draw the connectible ends of the brassière tight, to stretch the brassière on the form and to do so without fear of damage to any part of the garment itself.

More specifically, the object of the invention is realized through the medium of simple and practical mechanical means mounted in the rear open side of a mold or equivalent plastic form, said means being characterized by simple and readily mounted and usable complements which coincide with the requisite nicety and insure over-all resultfulness.

In carrying out a preferred embodiment of the invention, a fixture is mounted in the rear open side of the plastic or equivalent form and this is provided with two companion brackets, one of which is rigidly attached to the fixture and serves as a snubber and the other of which is slidably mounted and serves to take up slack and place the interconnected ends of the garment under tension, whereby said garment is effectively maintained on the form for practical display effects.

Then too, novelty is predicated on the aforementioned fixture and brackets, wherein the movable one includes a friction held sleeve or slide cooperating with a companion part of the fixture and which, when canted, retains itself in a desired position and when tripped with proper finger action, releases itself to relieve the tension on the interconnected ends so that they may then be readily separated and the brassière taken off the form without difficulty.

Other objects, features and advantages will

2

become more readily apparent through the following description and the accompanying sheet of drawings.

In the drawings, wherein like numerals are employed to designate like parts throughout the views:

Figure 1 is a perspective view, which may be called a rear view, and this shows the open side of the form and the means therein for tensioning the ends of the brassière and securing the latter in place.

Figure 2 is a bottom plan view of the structure seen in Figure 1.

Figure 3 is a perspective view similar to Figure 1, showing the parts in the positions which they occupy when the tension is removed or just prior to the time when the ends of the brassière are about to be connected and placed under tension.

Figure 4 is a section on the vertical line 4—4 of Figure 1 looking in the direction of the arrows.

Figure 5 is an exaggerated sectional and elevational view taken on the vertical line 5—5 of Figure 4 looking in the direction of the arrows.

The form, which is of commercial plastics or the like, is denoted generally by the numeral 6. This may be any conventional type of form on which a conventional brassière 8 is to be removably mounted for display and advertising purposes. The flap-like end portions of the brassière are denoted by the numerals 10 and 12, while one free or terminal end is denoted at 14 and this is provided with eyelets 16 to accommodate hooks 18 on the other end portion 20. As before stated, the form is open at the rear side, as denoted generally by the numeral 22. Means is provided in this open available space for taking up slack and placing the interconnected ends 14 and 20 under tension so as to stretch the garment on the form and to do so without having to use pins or other damaging fasteners. The means, generally speaking, is characterized by three companion components or parts; namely, fixture means 24 directly attached to the form, a first bracket 26 and a second bracket 28, said brackets being carried by said fixture.

The fixture is of inverted U-shaped form and has end portions 30 and 32 suitably fastened to the interior surfaces of what may be called the end wall portions 34—34 of the form. The intermediate or bight portion of the fixture, is denoted by the numeral 36 and it will be observed that this slants at an oblique angle, as best shown in Figure 4.

The first bracket 26 is a sort of a snubber and

it is of L-shaped form and one arm 38 overlies and is riveted at 40 to the intermediate portion of the bight portion 36. The longer arm 42 is cylindrical in cross-section and of any suitable length, and it depends at right angles from said bight portion.

The shiftable or relatively movable bracket is denoted by the numeral 28 and comprises an arm or leg 44 attached to a slide which takes the form of a sleeve 46. The sleeve slidably embraces the bight portion and has depending end portions 48-48 straddling and riveted or otherwise connected at 50 to the upper end of the arm. The sleeve is shaped to embrace the slightly pitched or obliquely inclined bight portion 36 in the manner best shown in Figure 4. This sleeve functions as sort of a friction clutch and when it is in a set position it occupies the tilted position seen in Figure 5, whereupon at least one edge "bites" into the bight portion and thus locks itself in a set position.

In practice, the brassière is fitted on the form to conform therewith in the manner shown, for example, in Figure 3 and the end portion 10 is looped over the shiftable bracket arm or leg 44 in the manner shown at 54. It is then provided with a sort of a return bend at 56 and the end portion 14 is now carried around over and situated over the leg or arm 42. The fasteners 16 and 18 are now joined and then the entire bracket 48 is shoved from its position, as shown in Figure 3 to the position shown in Figure 1, whereupon it places the bend or loop 54 under tension. In fact, the interconnected ends 10 and 12 are now tensioned by removal of the slack and when they are fully taut the bracket 28 is slightly tilted or canted so that it takes the friction clutch L-position, seen in Figure 5. When it is desired to remove the brassière from the form, the lower end of the leg 44 is tripped in the direction of the arrow A, as seen in Figure 5, whereupon the clutch is released and the bracket is then free to slide and to relieve the previously existing tension so that the fasteners 16 and 18 may now be uncoupled.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. Means for supporting, displaying and retaining a brassière in a display position comprising, in combination, a form open at its back, a fixture rigidly mounted in said form and accessible at the open back, and snubbing and tensioning means carried by said fixture, said last named means comprising a first bracket fixed on said fixture and a second bracket slidable on said fixture and movable toward and from the first bracket, said first bracket including a depending leg over which interconnected ends of the brassière may be snubbed, and said remaining bracket embodying a leg having a sleeve and said sleeve being slidably and tiltably mounted on said fixture.
2. Means for supporting, displaying and retaining a brassière in a display position with the ends of the brassière coupled together and fastened without requiring the use of pins as usual comprising, in combination, a form over which the brassière is applied and stretched and displayed more or less in a conventional manner, said form being open at its back, a substantially U-shaped fixture situated wholly within the confines of the form and accessible freely by way of the open back of the form and embodying lateral end portions suitably fastened to interior surfaces of end wall portions of the form and having an intermediate portion, a first bracket fixed on said intermediate portion and extending laterally therefrom, and a second bracket slidable on said intermediate portion and extending at right angles therefrom and adjustable toward and from the first bracket, said second bracket having a sleeve and said sleeve being slidably and pivotally mounted on said intermediate portion.
